UNITED STATES PATENT OFFICE.

ALFRED SAVILL TOMKINS, OF HOLMWOOD, CATERHAM, COUNTY OF SURREY, ENGLAND.

PORTABLE COOKING STOVE AND UTENSILS.

SPECIFICATION forming part of Letters Patent No. 404,578, dated June 4, 1889.

Application filed November 7, 1888. Serial No. 290,235. (No model.) Patented in England September 22, 1888, No. 13,728.

To all whom it may concern:

Be it known that I, ALFRED SAVILL TOMKINS, a citizen of England, captain in the Victoria Rifles, residing at Holmwood, Caterham, county of Surrey, England, have invented new and useful Improvements in Portable Cooking-Stoves, (for which I have made application for Letters Patent in Great Britain, which patent when granted will bear date 22d 10 day of September, 1888, No. 13,728,) of which the following is a specification.

This invention has for its object to provide a novel, simple, and efficient cooking-stove especially designed for use by military men or travelers in tents or wagons; and it consists in the features of construction and combination of devices hereinafter described, and specifically pointed out in the claim, reference being made to the accompanying drawings, in 20 which—

Figure 1 is a vertical section of a stove according to my invention; and Fig. 2 is a perspective view, to an enlarged scale, showing part of the upper edge of one of the stove-boilers with provision against spilling the contents when the stove is shaken by the movements of the wagon on which it may be carried.

From the fire F, which is situated in the upper part of the stove, the hot products of combustion pass across by the flue C, down the flue C', back by cross-flues C² to the chimney C², heating several ovens F', in which are cooking pans or vessels B².

On the top of the stove are placed boilers K, each of which, as shown in Fig. 2, is made near its upper edge with an outward bulge or

corrugation n, and above it with two walls p p', forming a trough, the inner wall of which p' is perforated with numerous holes, allowing such liquid as may enter the trough to flow back into the boiler. The cover of the boiler has two lips projecting down from it, the outer lip entering the trough between p and p' and the inner lip extending down within p'. Should the liquid contents of the boiler be agitated, the waves are arrested by the lips of the cover and the sides of the trough, so that none of the liquid is spilled.

At the back and sides of the stove there is a water-casing R, which protects against fire any combustible material in the neighborhood of the stove.

Having thus described the nature of this invention and the best means I know of carrying the same into practical effect, I claim—

A portable cooking apparatus consisting of fire-place F, flues C C' C², chimney C², ovens F', and boilers K, in combination with water-casing R, substantially as described.

In testimony whereof I have signed my name to this specification, in the presence of two subscribing witnesses, this 25th day of October, A. D. 1888.

ALF. SAVILL TOMKINS.
